CLAIM

The ornamental design for a network cable plug, as shown and described.

DESCRIPTION

FIG. 1 is a perspective view of a network cable plug showing my new design;

FIG. 2 is a front elevational view thereof;

FIG. 3 is an enlarged front view thereof;

FIG. 4 is a rear elevational view thereof;

FIG. 5 is an enlarged rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an exploded view thereof.

The broken lines in the drawings illustrate environmental features and portions of a network cable plug that form no part of the claimed design.
